US00D914722S

(12) **United States Design Patent** (10) **Patent No.:** **US D914,722 S**
(45) **Date of Patent:** **** Mar. 30, 2021**

(54) **DISPLAY SCREEN OR PORTION THEREOF WITH GRAPHICAL USER INTERFACE**

(71) Applicant: **SAMSUNG ELECTRONICS CO., LTD.**, Suwon-si (KR)

(72) Inventors: **Jihyun Lee**, Suwon-si (KR); **Cedric Kiefer**, Berlin (DE); **Henryk Wolllik**, Berlin (DE); **Jae Julien**, Suwon-si (KR); **Yoojin Choi**, Suwon-si (KR); **Daewung Kim**, Suwon-si (KR)

(73) Assignee: **SAMSUNG ELECTRONICS CO., LTD.**, Gyeonggi-Do (KR)

(**) Term: **15 Years**

(21) Appl. No.: **29/710,564**

(22) Filed: **Oct. 24, 2019**

(30) **Foreign Application Priority Data**

Apr. 25, 2019 (KR) 30-2019-0019671

(51) **LOC (13) Cl.** **14-04**

(52) **U.S. Cl.**

USPC **D14/486**

(58) **Field of Classification Search**

USPC D14/485-495

CPC G06F 3/048-04897

(57) **CLAIM**

The ornamental design for a display screen or portion thereof with graphical user interface, as shown and described.

DESCRIPTION

FIG. 1 is a front view of a first embodiment of a display screen or portion thereof with graphical user interface, showing our new design;

FIG. 2 is a front view of a second embodiment thereof; and, FIG. 3 is a front view of a third embodiment thereof.

The outermost perimeter illustrated by a pair of dashed broken lines depicts a display screen or portion thereof and forms no part of the claimed design.

1 Claim, 3 Drawing Sheets
